UNITED STATES PATENT OFFICE

CARY E. FERGUSON AND CHARLES E. SHOCKENCY, OF LIMA, OHIO

FLUE MARKER

Application filed February 28, 1930. Serial No. 432,276.

This invention relates to an appliance which is hereinafter referred to briefly as a flue marker, and it has more particular reference to an appliance in the form of an attachment to be used on a conventional flue cutter, wherein said appliance is especially designed and constructed for marking rotary flues and boiler tubes.

In carrying the invention into practice, we have evolved and produced a structure which is believed to be a novel contribution to the art, a structure which is original and characteristic in that it embodies appropriately related details for accomplishing the desired results in a practical and feasible manner.

Furthermore, we have developed a novel structural organization of parts which are co-related in a manner to provide a structure which is susceptible of accurate manipulation, and which is otherwise dependable in fulfilling the requirements of an appliance of this class.

In the drawings:

Figure 1 is an elevational view showing the complete appliance as constructed in accordance with our invention.

Figure 2 is a vertical sectional view at right angles to Figure 1.

Referring now to the drawings by reference numerals, attention is first called to the character 3. This designates an existing oscillatory operating shaft on a conventional flue cutting machine (not shown).

In accordance with the present invention, we provide an operating arm including a substantially vertical portion 4 and a horizontal portion 5 at the upper end. The lower end portion of the part 4 is constructed as at 6 to provide one-half section 6 of the clamp which embraces the shaft 3. The complementary or companion section of the clamp is indicated at 7.

Attached to the upper end of the horizontal part 5 is a U-shaped carrier frame 8. The upstanding arm portions of this frame are provided with bearing holes to accommodate a rocker shaft 9. On one end of this shaft is a rocker arm 10 to which a return coiled spring 11 is connected. The

opposite end of the spring is fastened to an outstanding bracket 12 on the frame.

The rock shaft includes a substantially rectangular portion 13 constructed to support a plurality of horizontally aligned bristles generally designated by the numerals 14. These brushes are removably held in place by the set screws 15. The brushes are projected normally in a horizontal plane to engage the rotating boiler flue at F. Incidentally, the numeral 16 designates a depending operating link which is connected with the rocker arm 10 and which is in turn connected with a suitable operating means for rocking the shaft 9 with respect to the fluid containing pan or receptacle 17.

The marking fluid receptacle 17 is of the shape shown in the drawings. It is provided to be suspended by hangers 18 mounted on the end portions of the rock shaft so as to be self levelling. The supporting arm 4, the frame 8, and the receptacle 17, with the brushes and rock shaft constitute a unit which is swung by the shaft 3 toward and away from a flue F, into operative, marking position or into inoperative position which is indicated by the dotted lines in Figure 2. The brushes 14 are normally maintained in a horizontal marking plane, but they swing to a downward vertical position and dip into the flue in the receptacle 17 to re-prime them with marking fluid, when the unit moves into the inoperative position shown by the dotted line in Figure 2. The link 16 operates or is operated to swing the brushes 14 into the pan 17 as the unit is moved from operative to inoperative position.

Persons skilled in the art to which the invention relates, and persons familiar with conventional flue cutting machines will be able to appreciate the novelty of this appliance, the ease with which it may be attached to the conventional filing machine, and as well as other features and advantages accompanying the invention. Consequently, a more lengthy description is regarded as unnecessary.

It is to be understood that minor changes in the shape, size and rearrangement of elements which fall within the field of inven-

tion embodied in the accompanying claims may be resorted to in actual practice if desired.

We claim:

- 15 1. In a structure of the class described, in combination, an oscillatory operating shaft, a liquid containing receptacle supported thereon and bodily movable therewith, and a multiple brush assembly associated with the pan and movable with said pan and also movable independently of the pan for replenishing purposes.
- 16 2. In a structure of the class described, in combination, an operating shaft, a frame connected to said shaft, a self-levelling liquid containing pan mounted on said frame, a rock-shaft mounted on said frame, a marking brush carried by said rock-shaft and cooperable with said receptacle.
- 20 3. In a structure of the class described, an operating shaft, an arm rising therefrom, means for clamping said arm on said shaft, a frame carried by said arm, a self-levelling fluid pan carried by said frame, marking brushes mounted on said frame and swingable into said pan, and operating means for said brushes.
- 25 4. In a structure of the class described, in combination, a U-shaped frame, a rock shaft mounted for rocking motion in bearing holes in the arms of said frame, a rocker arm on said shaft, a depending actuating link for said rocker arm, a plurality of removable marking brushes carried by said rock shaft, a return spring for maintaining the brushes normally in a horizontal plane, hangers carried by said pan and suspended from said rock shaft to render said pan substantially self-levelling, and means for mounting the frame on an oscillatory operating shaft.

In testimony whereof we affix our signatures.

CARY E. FERGUSON.
CHARLES E. SHOCKENCY.
